(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter illustrated by dashed broken lines in the FIGURE illustrates a display screen or portion thereof and forms no part of the claimed design. The remaining dashed broken lines in the FIGURE illustrate portions of the graphical user interface that form no part of the claimed design.

1 Claim, 1 Drawing Sheet

Exercise X

22 Jan 00:00

What exercise did you do?
e.g., Run, walk

Please log each exercise as a separate item

Duration

45 min - +

UingoCounts from exercise spikes (during exercise and 30 min before and after) will not be added to your daily target

Save and close
